G. STRIFFLER

APPARATUS FOR FILTERING AND BOTTLING FLUIDS UNDER PRESSURE

Filed Jan. 20, 1928

INVENTOR:
Gottlieb Striffler
BY
Ernest J. Michaelis

ATTORNEY.

UNITED STATES PATENT OFFICE.

GOTTLIEB STRIFFLER, OF CHICAGO, ILLINOIS.

APPARATUS FOR FILTERING AND BOTTLING FLUIDS UNDER PRESSURE.

Application filed January 20, 1928. Serial No. 248,077.

The invention relates to apparatus for bottling fluids under pressure and especially effervescent fluids, which are to be filtered at the same time they are bottled.

5 The present invention is an improvement on my invention covered in the copending application Serial No. 236,309 filed Nov. 28, 1927.

10 10 provide a bottling and filtering device the different compartments whereof are all formed by one integral container.

15 Other objects of the invention not specifically mentioned may be easily ascertained and understood from the following description in connection with the accompanying drawings forming a part thereof. It is however to be noted, that the invention is not to be limited or restricted to the exact 20 construction or formation shown in the drawings and described in the specification, but that the invention is only to be limited by the scope of the claims appended hereto.

25 In the drawings:

Fig. 1 is an elevation of the apparatus according to the present invention, and

Fig. 2 is a vertical section through said apparatus.

30 The body of the device consists of a container 5 preferably made from sheet copper. At the top said container is provided with a flange 6. This flange is created by bending the metal, of which the container is made, outwardly at right angles to the walls of said container, and then bending the metal forming the flange back upon itself, so that the flange consists of two layers of metal. In order to reinforce the flange still more a 35 steel ring 7 may be clamped in between the two layers of metal mentioned above.

40 To close the container 5 a lid 8 is provided. This lid has a flange 9, which is made in the same way as the flange 6. On the latter a plurality of clamps 10 are hingedly fastened, which can be swung into clamping position as shown in the drawings to engage the flange of the lid and force the same down onto the container. A rubber ring 11 or any other suitable packing ring may be arranged between the two flanges, so that the lid will close the container hermetically, when the clamps are forced down onto the flange 9 of the lid.

45 50 The container may be provided with a plurality of legs 12. In a distance of about one third of the height of the container from

the bottom a supporting ring 13 or the like is fastened to the inner face of the container, and a comparatively strong false bottom plate 14 rests on said ring. A spacer ring 15 is placed on top of said plate and a coarse sieve plate 16 is supported by said spacer ring. On top of this sieve plate a fine sieve plate 17 is located, and this plate carries a layer of filter material 18, for instance cotton. Another fine sieve plate 19 rests on said filter material and a second coarse sieve plate 20 is arranged on top of the last named plate. A second spacer ring 21 rests on top of the plate 20 and abuts with 55 its upper rim the lid 8. When the filter material is arranged in its place it is loosely packed, so that the upper rim of the ring 21 extends somewhat beyond the container. When then the lid is forced down, the filter 60 material is compressed, and the plate 14 is forced upon the supporting ring 13. In order to make the connection between the plate and the ring leak-proof a packing ring 22 or the like may be arranged between the two members. A short inlet pipe 23 provided with a valve 24 leads into the 65 interior of the container adjacent the upper rim thereof, and a baffle plate 25 is fastened to the inner face of the container in such a manner, that any liquid entering the container through the inlet pipe will be deflected against the wall of the container and will flow down on said wall instead of falling freely onto the filter. In this manner 70 objectionable foaming of the liquid to be treated is obviated. The spacer ring 21 has a cut-out portion, as indicated in Fig. 2 to permit of the mounting of the baffle plate 25 and the entrance of the fluid to be treated.

75 80 85 From the space between the plate 14 and the sieve plate 16 a pipe 26 leads to the space below the plate 14, and in this pipe a valve 27 is arranged. A slot or opening is provided in the spacer ring 21 to permit the pipe 26 to communicate with the interior of the container. Adjacent the place where the pipe 26 enters the space below the plate 14, a second baffle plate 28 is fastened to the inner 90 face of the wall of the container for the same purpose as described above with reference to the baffle plate 25.

95 100 105 Into the wall of the container two fluid gauges 29 and 30 are set, the one above the level of the upper coarse sieve plate 20, when the lid is pressed down onto the container, and the other one below the level of the

plate 14. A manometer 31 may be arranged on the lid 8.

A tank 32 is fastened in any convenient manner to the outside of the container, and adjacent said tank an air pump 33 is also mounted on said container. A tube 34 leads from the pump to the tank, so that compressed air may be stored in said tank. A pipe 35 leads from the tank into the upper 10 part of the container and a stop cock 36 in said pipe serves to regulate the flow of compressed air from the tank into the upper part of the container. From the lower portion of the tank a pipe 37 leads into the portion 15 of the container below the plate 14. A stop cock 38 regulates the flow of compressed air through this pipe. A nipple 39 is provided on the tank and a stop cock 40 regulates the flow of compressed air through 20 said nipple. Adjacent the bottom of the container a cock 41 is arranged for draining the fluid from the lower portion of the container. In order to let the superfluous air out of the lower portion of the container a 25 valve 42 is provided.

The device is operated in the following manner: The liquid to be treated is brought into the upper portion of the container in any convenient manner. When for instance 30 the liquid to be treated is in a can, the lid 8 may be removed and the liquid may then be poured into the container, whereupon the lid is fastened tightly onto the container by means of the clamps 10. Or, if the liquid to 35 be treated should be contained in a demijohn or the like a tube extending through the cork of the demijohn may be immersed into the fluid to be treated and the other end of the tube may then be attached to the inlet 40 pipe 23. Another tube may be fastened to the nipple 39 and may lead through the cork of the demijohn. The valve 24 and the cock 40 are opened, after the lid 8 has been seated firmly upon the container by tightening the 45 clamps 10. The compressed air flowing from the tank 32 into the demijohn forces the liquid into the container. When the liquid gauge shows, that a certain amount of liquid is in the upper part of the container, the 50 valve 24 may be closed and also the cock 40. The cock 36 on the pipe 35 will then be opened, so that compressed air will flow into the upper part of the container and will force the liquid therein through the sieve

plates and the filter material. The valve 55 27 is opened and the filtered liquid will flow into the lower portion of the container. If the liquid being treated is an effervescent liquid, such as ginger ale or the like, it is necessary to keep the liquid continuously 60 under pressure, and for that purpose the cock 38 in pipe 37 is opened permitting compressed air to flow into the part of the container underneath the false bottom plate 14.

By opening the cock or spigot 41 the 65 filtered liquid may be drawn from the container, while the liquid is under pressure.

What I claim as new is:

1. In a device of the class described a container, a lid therefor, means for seating 70 said lid tightly and firmly onto the container, a false bottom in said container arranged at a distance from the real bottom thereof, a filter arranged in said container at a distance above said false bottom, an air compressing device communicating with the top portion of the container, an inlet pipe communicating with said portion, a pipe connecting the space between the filter and the false 75 bottom with the space beneath said false bottom, means for conducting compressed air into said last named space, and an outlet on the container adjacent the bottom thereof. 80

2. In a device of the class described a container, a removable lid therefor, means for 85 clamping said lid tightly onto the container, a false bottom arranged in said container at a distance above the real bottom, a spacer ring seated on the false bottom, a sieve plate resting on said ring, a filter material arranged on said sieve plate, a second sieve plate on top of said filter material, a second spacer ring seated on said upper sieve plate, the lid being adapted to engage the upper 90 rim of said ring and to force it downwardly, 95 when the lid is being clamped tightly onto the container, an inlet communicating with the top portion of the container, an air compressing means communicating with the same portion, a pipe connecting the space 100 between the filter and the false bottom with the space underneath said false bottom, means for conducting compressed air into said last named space, and an outlet on the container adjacent the bottom thereof.

In witness whereof I affix my signature.

GOTTLIEB STRIFFLER.
